UNITED STATES PATENT OFFICE.

CLEN S. HUMPHREY, OF BROOKLYN, NEW YORK.

DESIGN FOR A CAP FOR A POWDER-CONTAINER.

54,745.

Specification for Design.

Patented Mar. 23, 1920.

Application filed April 29, 1919. Serial No. 293,575. Term of patent 7 years.

To all whom it may concern:

Be it known that I, CLEN S. HUMPHREY, a citizen of the United States, and a resident of the city of New York, borough of Brooklyn, in the county of Kings and State of New York, United States of America, have invented a new, original, and ornamental Design for a Cap for a Powder-Container, of which the following is a specification, reference being had to the accompanying drawing, forming part thereof.

The cover is adapted to be used on the usual sifter top powder can, as a cover therefor. The design comprises essentially three cylindrical portions of different diameters, the cylindrical portions also being of a different thickness or height. The cylindrical portion having the greatest thickness and the largest diameter is ar-

ranged uppermost, the cylindrical portion next largest in diameter, and of least thickness, is arranged at the lower portion, the upper part of said portion tapering inwardly to the neck portion of the cover which is of the smallest diameter, and positioned between the upper and lower cylindrical portions of the cover. Each of the above mentioned cylindrical portions have clear cut and well defined corners.

Figure 1 is a plan view of the container cap.

Fig. 2 is an elevation of the cap.

I claim:

The ornamental design for a cap for a powder container, substantially as shown and described.

CLEN S. HUMPHREY.
